DESIGN FOR A MILK CAN

J. Neil Palmer, Milwaukee, Wis., assignor to
Geuder, Paeschke & Frey Co., Milwaukee, Wis.,
a corporation of Wisconsin

Application April 4, 1940, Serial No. 91,469

Term of patent 7 years

To all whom it may concern:

Be it known that I, J. Neil Palmer, a citizen of the United States, residing at Milwaukee, in the county of Milwaukee and State of Wisconsin, have invented a new, original, and ornamental Design for a Milk Can, of which the following is a specification, reference being had to the accompanying drawing, forming a part thereof, and in which:

Figure 1 is a view in side elevation of a milk can showing my new design; and

Figure 2 is a view thereof in top plan.

The dominant features of my design reside in the portion shown in solid lines.

I claim:

The ornamental design for a milk can, as shown and described.

J. NEIL PALMER.
